TRAIN CONTROL SYSTEM

John Tacza, Pittsburgh, and John C. Elder, Penn Township, Allegheny County, Pa., assignors to Westinghouse Air Brake Company, Wilmerding, Pa., a corporation of Pennsylvania

Filed June 22, 1959, Ser. No. 821,911
9 Claims. (Cl. 246—3)

Our invention relates to a train control system, and particularly to an arrangement for controlling the movements of trains of cars from a receiving yard to the crest of the hump in a gravity or hump type railway car classification yard.

In railway freight operations the road engines pull their trains of cars into what is commonly known as a receiving yard located at a division point or other point on the railroad where the cars must be reclassified into new trains according to class, destination, etc. The receiving yard usually consists of a number of storage tracks where each train of cars arriving is stored until the classification yard is available for reclassifying the cars in the train. In some track layout arrangements the storage tracks all connect over one or more hump lead or "shove-up" tracks to a single track in approach to the hump in a gravity or hump type classification yard. Switch or humping engines shove the trains of cars up the shove-up tracks to the vicinity of the crest of the hump where each car or groups of cars of a similar classification are separated from the rest of the train by a brakeman and then proceed by gravity to their proper classification tracks.

In order to provide for safer operation in such railway operations it has been found expedient to provide a system whereby indications can be given to the engineman of the shove-up engines whether they are to proceed with the shove-up movement of their train of cars or to stop. Such a system is especially important in track layouts where two or more shove-up tracks leading to the hump approach track exist, and more than one switching engine may be shoving trains of cars up different shove-up tracks preparatory to the movement of the cars over the hump for classification purposes. It is accordingly one object of our invention to provide an economical system for furnishing indications to the enginemen of the shove-up engines which inform each engineman whether he is to proceed with his train movement or to stop.

It is another object of our invention to provide said indications independent of any conductors such as the rails of the track or cable or line wires between the apparatus controlling the indications and the indicators for giving the indications to the enginemen.

It is a further object of our invention to provide an indicating system of the type described in which it is insured, insofar as practicable, that an indication to proceed into the hump approach track will not be given to more than one engineman at a time.

Other objects and characteristic features of our invention will become apparent as the description proceeds.

In accomplishing the foregoing objects of our invention we employ a wireless communication system over which signals are transmitted, under the control of manually operated devices to indicator control apparatus for each engine, to the engineman of which it is desired to give indications.

We shall describe one form of apparatus embodying our invention and shall then point out the novel features thereof in claims.

2

In the drawings:

FIG. 1 is a diagrammatic view showing a simplified track layout, and the manual control devices and associated apparatus for controlling the transmission of the indicator control signals.

FIG. 2 is a diagrammatic view showing the communication arrangement and associated apparatus for transmitting and receiving the signals for providing the indications to the enginemen of the shove-up engines.

It is believed expedient at this time to point out that hereinafter in this description the term "signal" shall refer to a signal transmitted over said wireless communication system, as the term is often employed in the wireless or radio communication art.

It is also believed expedient at this time to point out that the wireless communication apparatus employed in our invention and illustrated in FIG. 2 is shown, for purposes of simplification, in block diagram form since the details thereof form no part of our present invention and such apparatus is well known. The power supply for operation of the communication apparatus is not shown in the drawings but is intended to be considered as included in the block diagrams representing said communication apparatus. This apparatus will be discussed 25 more fully hereinafter in this description.

Referring now to FIG. 1 there is shown at the top of the drawing, in single line form, a track layout including a stretch of single track extending from a track switch, designated by the reference character SW, in the right hand direction on the drawing, to a point designated as the crest of hump which is intended to indicate the crest of the hump in a gravity or hump type railway car classification yard. This single track stretch is sometimes referred to hereinafter as the main track, the hump approach track, or merely as the single track. Extending in the left-hand direction on the drawing from switch SW are two stretches of track 1 and 2 sometimes referred to hereinafter as yard tracks, shove-up tracks, multiple track leads, or hump approach track leads. The yard tracks converge at switch SW to form the hump approach track. Railway cars being moved toward the hump for classification move in the direction indicated by the arrow above the track layout.

Three insulated track sections are provided in the tracks of the track layout. One of these sections is designated HAT and extends, from a point just short of the crest of the hump, to the point of fouling or clearance in each of the yard tracks. The remaining two insulated track sections designated 1T and 2T are located in tracks 1 and 2, respectively, and each extends from the point of clearance in its respective yard track to a predetermined point on that track so as to form a track section of sufficient minimum length that it cannot be spanned by the trucks and wheels of the longest railway car or engine to be moved over the track.

Each of the insulated track sections is provided with a track circuit including a source of track circuit current and a track relay in a manner well known in the art such that the track relay is energized when no car or engine occupies the track section. For purposes of simplicity the sources of current are not shown in the drawing, and the track relays designated 1TR, 2TR and HATR for track sections 1T, 2T and HAT, respectively, are shown connected to their respective track sections in a conventional manner by a dotted line extending from each track section to the respective track relay.

There is shown on the left-hand side of FIG. 1 a plurality of manually operable push-pull type of circuit controllers designated F1T1PB, F2T1PB, F1T2PB, and F2T2PB. These controllers are shown disposed on a panel, designated as a receiving yard control panel, but

may be mounted in any manner desired and at any location convenient to the personnel who are to control the shove-up train movements from the receiving yard toward the rest of the hump. These controllers are each shown as having a movable contact *a* normally closed against a back contact point and operable to close against a front contact point when the respective controller is depressed. Controllers F1T1PB and F2T1PB are noted on the drawing as interlocked with each other, and are also of the stick type. That is, when one of these controllers is pushed or depressed, it will remain in that operated position until it is pulled to return it to its normal position, or until the other controller is depressed. Upon the depression of said other controller the interlocking feature of the controllers operates the first controller to open its front contact point before the front contact point of the subsequently depressed controller closes. Controllers F1T2PB and F2T2PB are also interlocked with each other and are of the stick type, and operate in a manner identical to that described for the other two interlocked controllers.

There is shown on the lower right-hand side of FIG. 1 an additional manually operable circuit controller designated SCL and comprising a lever operated contact member designated CM. This controller is shown as normally occupying a center or "off" position in which the contact member is closed against a contact point designated 0, and is operable to left and right-hand positions designated T1 and T2, respectively, in which the contact member is closed against contact points designated 1 and 2, respectively. This circuit controller is shown disposed on a hump control panel but may be mounted in any manner desirable and at any location convenient to the personnel who are to control the actual train "humping" movements. Although in most hump type classification yards the movements of trains from the receiving yard to a position for humping and the train humping operations themselves are controlled by different personnel, and, therefore, the receiving yard control panel and the hump control panel would usually be located at different locations as shown in FIG. 1, it is to be understood, that the manually operable circuit controllers shown in our drawings as disposed on two separate panels could be located so as to be controlled by the same person without departing from the scope of our invention. The purpose of the described manually operable circuit controllers will be more fully set forth later in this description.

Referring further to FIG. 1, there is shown a group of relays designated F1T1SR, F2T1SR, F1T2SR, and F2T2SR. These relays are modulating frequency control stick relays for yard tracks 1 and 2, and repeat, in a manner to be hereinafter described, the operation of an associated one of manually operable controllers F1T1PB, F2T1PB, F1T2PB, or F2T2PB. Relays LOPR, LT2SR and LT1SR in FIG. 1 are relays actuated by the operation of the manually operable controller SCL and the operation of these relays will also be described later in this description.

Two additional relays designated HA1TSR and HA2TSR are shown in FIG. 1. These relays are track repeater stick relays which serve to provide control for circuits, the proper operation of which depends on whether a train enters track section HAT from yard track 1 or 2. The operation of these relays will be described in detail later in this description.

There is shown at the top of FIG. 2 of the drawings the transmitting or communication apparatus employed in our invention for the transmission of control signals to the enginemen on the shove-up engines, and the circuit arrangement for controlling the transmission of said signals. The transmitting apparatus is shown as including a transmitter or carrier oscillator, modulator, and amplifier unit designated TMU. This unit generates a carrier frequency which is supplied to output terminal *b* on the unit and thence to a transmitting antenna design-

nated TANT. The carrier frequency generated by unit TMU is selectively modulated by two audio frequencies supplied to input terminal *a* of the unit over signal selection circuits, to be described, from output terminals *a* and *b* of an audio oscillator unit designated AOU. These audio modulating frequencies are designated No. 1 and No. 2 and are supplied from the output terminals *a* and *b*, respectively, of unit AOU. While we have shown only two such audio modulating frequencies it is to be understood that any number of such frequencies could be employed to transmit additional signals within the scope of our invention. The apparatus for generating, modulating and amplifying the signals to be transmitted is shown in the drawings in block diagram form because, as previously mentioned, the details of this apparatus form no part of our present invention and such apparatus is well known.

On the lower part of FIG. 2 of the drawings is shown two sets of signal receiving and indicator equipment designated engine A equipment and engine B equipment. Only two sets of such equipment are shown because in the specific example of our invention described herein only two audio modulating frequencies are employed and, therefore, only two engines are shown provided with such equipment. However, in actual practice each engine to be employed as a shove-up engine would be provided with a set of the equipment and the equipment of all engines to be working simultaneously as shove-up engines would be tuned to be responsive to a different audio modulating frequency, the number of such frequencies employed being increased to correspond to the number of engines employed simultaneously as shove-up engines. For example, assuming that four yard tracks exist leading to a hump approach track in a track layout similar to that shown in FIG. 1, two, three or four shove-up engines could be working simultaneously, and a different audio modulating frequency would be assigned to each such engine. Arrangements would also be provided to assign any of the frequencies to any of the four yard tracks. This will become more apparent later in this description.

Referring further to the aforementioned engine equipment, the equipment on engines A and B is, with the exception of the modulating frequency to which the equipment is tuned, identical, engine A equipment being assumed to be tuned to audio frequency No. 1 and engine B equipment to audio frequency No. 2. Therefore, only the equipment for engine A will be described in some detail. The receivers or carrier amplifiers, frequency selection, and audio amplifier units designated ARU and BRU for engines A and B, respectively, are shown in block diagram form because the details of these receivers or receiving units, similarly to the previously described transmitting apparatus, form no part of our present invention and such receiving units are well known.

Referring now to the engine A equipment, there is associated with receiving unit ARU an antenna designated ARANT which receives the signals transmitted by the transmitter TMU and supplies the signals to an input terminal *a* on receiver ARU. The frequency selection portion of the receiver selects or is responsive only to audio modulating frequency No. 1 and if the carrier frequency received is modulated by that audio frequency an output is produced at output terminal *b* of unit ARU which is supplied to a demodulator relay designated ASCR to thereby pick up that relay. A contact *a* of relay ASCR functions to control lamps of an indicator designated ACS in a manner described hereinafter.

A source of current such as a battery of proper voltage and capacity is provided for the indicator associated with each of the shove-up engines A and B. These sources of current for purposes of simplicity are not shown in the drawing, but the positive and negative terminals of these sources are designated AEB and AEN

respectively, and BEB and BEN, respectively, for the indicators for engines A and B, respectively.

When the carrier frequency transmitted by unit TMU is not modulated by audio frequency No. 1, demodulator relay ASCR described above is released and a circuit is closed over the back point of contact *a* of that relay to energize the S or stop lamp of indicator ACS. This circuit extends from terminal AEB of the associated source of current over the back point of contact *a* of relay ASCR and through the filament of said S lamp to terminal AEN of said source. The S lamp is thus illuminated and indicator ACS gives a stop indication.

When transmitter TMU is transmitting the carrier frequency modulated by audio frequency No. 1, in a manner to be hereinafter described, demodulator relay ASCR will pick up, opening at the back point of its contact *a* the energizing circuit for lamp S of indicator ACS, and closing at the front point of its contact *a* the energizing circuit for the Y or proceed lamp of indicator ACS. This circuit extends from terminal AEB of the source over the front point of contact *a* and through the filament of the Y lamp to terminal AEN. Lamp S of indicator ACS is thus extinguished and lamp Y is illuminated to indicate to the engineman of engine A that he may proceed.

The engine B equipment, as previously stated, is identical to and operates in an identical manner as that of engine A except that the frequency selection portion of the receiving unit BRU of engine B is tuned to be responsive to audio modulating frequency No. 2. Antenna BRANT, receiver unit BRU, demodulator relay BSCR and indicator BCS correspond, respectively, to the described equipment of engine A designated ARANT, ARU, ASCR and ACS.

It is believed expedient at this time to point out that a source of current such as a battery of proper voltage and capacity is provided for operation of the apparatus shown in FIG. 1. However, for purposes of simplicity, this source is not shown in the drawings but its positive and negative terminals are designated B and N, respectively.

It should also be pointed out in the drawings that the contacts of the various relays are not in all instances located below the rectangles representing the windings of the respective relays, but in each instance in which a contact is not so located it is identified by the reference character designating its respective relay disposed on the drawing directly above the movable portion of the contact. This arrangement is believed readily apparent from a brief glance at the drawings.

Referring again to FIG. 1 of the drawings and specifically to relays F1T1SR, F2T1SR, F1T2SR, and F2T2SR, the control circuits for these relays will now be described. Relay F1T1SR has a pickup circuit which extends from terminal B of the battery over the back point of contact *a* of controller F2T1PB, the front point of contact *a* of controller F1T1PB in its depressed or actuated position, back contact *b* of relay F2T1SR, back contact *b* of relay F2T1SR, and through the winding of relay F1T1SR to terminal N of the battery.

Relay F2T1SR has a pickup circuit which extends from terminal B of the battery over the back point of contact *a* of controller F1T1PB, the front point of contact *a* of controller F2T1PB in its depressed or actuated position, back contact *b* of relay F2T2SR, back contact *b* of relay F1T1SR, and through the winding of relay F2T1SR to terminal N of the battery.

Relays F1T1SR and F2T1SR each have a stick circuit part of each of which is a multiple circuit common to both stick circuits. These circuits extend from terminal B of the battery over back contact *c* of relay 1TR or over back contact *c* of relay HA1TSR, and thence over front contact *a* of relay F1TSR through the winding of that relay to terminal N of the battery, or over front contact *a* of relay F2T1SR through the winding of that relay to terminal N of the battery.

Relay F1T2SR has a pickup circuit which extends from

terminal B of the battery over the back point of contact *a* of controller F2T2PB, the front point of contact *a* of controller F1T2PB in its depressed or actuated position, back contact *c* of relay F1T1SR, back contact *c* of relay F2T2SR, and through the winding of relay F1T2SR to terminal N of the battery.

Relay F2T2SR has a pickup circuit which extends from terminal B of the battery over the back point of contact *a* of controller F1T2PB, the front point of contact *a* of controller F2T2PB in its depressed or actuated position, back contact *c* of relay F2T1SR, back contact *c* of relay F1T2SR, and through the winding of relay F2T2SR to terminal N of the battery.

Relays F1T2SR and F2T2SR each have a stick circuit part of each of which is a multiple circuit common to both stick circuits. These circuits extend from terminal B of the battery over back contact *c* of relay 2TR or back contact *c* of relay HA2TSR, and thence over front contact *a* of relay F1T2SR and front contact *a* of relay F2T2SR through the windings of the respective relays to terminal N of the battery.

The purpose of the back points of contacts *a* of controllers F1T1PB and F2T1PB in the pickup circuits for relays F2T1SR and F1T1SR, respectively, is to provide a check that the previously described interlocking between the two controllers is intact and operating. The back points of contacts *a* of controllers F1T2PB and F2T2PB in the pickup circuits of relays F2T2SR and F1T2SR, respectively, provide a similar check on the interlocking between those two controllers. The back contacts of relays F1T2SR and F2T1SR in the pickup circuits for relays F1T1SR and F2T2SR insure that these latter relays cannot be picked up to assign audio modulating frequency No. 1 to track 1 or audio modulating frequency No. 2 to track 2 when these frequencies are, as hereinafter described, respectively assigned to track 2 and track 1, as reflected by relays F1T2SR and F2T1SR, respectively, being maintained picked up over their stick circuits. Similarly, the back contact of relays F1T1SR and F2T2SR in the pickup circuits for relays F2T1SR and F1T2SR insure that these latter relays cannot be picked up to assign audio modulating frequency No. 2 to track 1 or audio modulating frequency No. 1 to track 2 when these frequencies are, as hereinafter described, respectively assigned to track 2 and track 1, as reflected by relays F2T2SR and F1T1SR being maintained picked up over their stick circuits. The utility of this arrangement will become more apparent later in this description.

The control circuits for relays HA1TSR and HA2TSR shown in FIG. 1 will now be described. Relay HA1TSR has a first pickup circuit extending from terminal B of the battery over front contact *a* of relay HATR and through the winding of relay HA1TSR to terminal N of the battery. Relay HA1TSR has a second pickup circuit extending from terminal B of the battery over back contact *b* of relay HA2TSR and through the winding of relay HA1TSR to terminal N of the battery. Relay HA1TSR has a multiple stick circuit extending from terminal B of the battery over front contact *a* of relay 1TR or front contact *c* of relay LT2SR, and thence over front contact *a* of relay HA1TSR and through the winding of the relay to terminal N of the battery.

Relay HA2TSR has a first pickup circuit extending from terminal B of the battery over front contact *b* of relay HATR and through the winding of relay HA2TSR to terminal N of the battery. Relay HA2TSR has a second pickup circuit extending from terminal B of the battery over back contact *b* of relay HA1TSR and through the winding of relay HA2TSR to terminal N of the battery. Relay HA2TSR has a multiple stick circuit extending from terminal B of the battery over front contact *a* of relay 2TR or front contact *c* of relay LT1SR, and thence over front contact *a* of relay HA2TSR and through the winding of the relay to terminal N of the battery. The operation and purpose of relays HA1TSR

and HA2TSR will be described more fully later in this description.

Relay LOPR shown in FIG. 1 is a slow release relay as indicated by the arrow drawn in the downward direction through the movable portion of contacts *a* and *b* of the relay in the pickup circuits, to be described, for relays LT2SR and LT1SR, respectively. Relay LOPR repeats the off position of controller SCL, that is, a pickup circuit for the relay is closed when lever SCL is in its off position. This circuit extends from terminal B of the battery through movable contact member CM of controller SCL, contact 0 of controller SCL and through the winding of the relay LOPR to terminal N of the battery. The purpose of the relay and its slow release feature will be discussed hereinafter.

Relay LT1SR in FIG. 1 is employed to at times repeat the T1 position of controller SCL, that is, a pickup circuit for the relay is prepared when controller SCL occupies its T1 position and is closed when either relay 1TR or HATR is released. This circuit extends from terminal B of the battery over said movable portion CM of controller SCL, contact 1 of controller SCL, back contact *b* of relay 1TR and back contact *c* of relay HATR in multiple, and thence over said front contact *b* of relay LOPR and through the winding of relay LT1SR to terminal N of the battery. Relay LT1SR has a stick circuit including its own front contact *a* which by-passes said contact *b* of relay LOPR in the described pickup circuit for relay LT1SR.

Relay LT2SR in FIG. 1 is employed to at times repeat the T2 position of controller SCL, that is, a pickup circuit for the relay is prepared when controller SCL occupies its T2 position and is closed when either relay 2TR or HATR is released. This circuit extends from terminal B of the battery over said movable portion CM of controller SCL, contact 2 of controller SCL, back contact *b* of relay 2TR and back contact *d* of relay HATR in multiple, and thence over said front contact *a* of relay LOPR and through the winding of relay LT2SR to terminal N of the battery. Relay LT2SR has a stick circuit including its own front contact *a* which by-passes said contact *a* of relay LOPR in the described pickup circuit for relay LT2SR.

Front contacts *a* and *b* of relay LOPR in the pickup circuits for relays LT2SR and LT1SR, respectively, insure that these latter relays cannot be picked up following a previous pickup and release of the respective relay, without first returning controller SCL to its off position. The slow release feature of relay LOPR insures that contacts *a* and *b* of that relay will remain closed for a sufficient period of time to permit relay LT1SR or LT2SR to pick up when controller SCL is moved from its off position to position T1 or T2, respectively. The utility and operation of relays LOPR, LT1SR and LT2SR will become more apparent as this description proceeds.

Referring again to the signal transmitting arrangement shown at the top of FIG. 2 of the drawings, the control circuits for supplying audio modulating frequencies No. 1 and No. 2 from unit AOU to transmitter unit TMU will be described.

Modulating frequency No. 1 when assigned to track 1, as hereinafter described, is supplied from output terminal *a* of unit AOU to input terminal *a* of unit TMU by first and second circuit paths, the first extending from said output terminal *a* over front contact *d* of relay F1T1SR, front contact *d* of relay 1TR, and front contact *e* of relay HA1TSR to said input terminal *a*; and the second extending from said output terminal *a* over said front contact *d* of relay F1T1SR, front contact *b* of relay LT1SR, and over front contact *d* of relay HA2TSR to said input terminal *a*. Modulating frequency No. 2, when assigned to track 1 as hereinafter described, is supplied from output terminal *b* of unit AOU to input terminal *a* of unit TMU by the same first and second circuit paths first described except that front contact *d*

of relay F2T1SR supplies modulating frequency No. 2 to said circuit paths in place of front contact *d* of relay F1T1SR supplying modulating frequency No. 1 to those paths.

Modulating frequency No. 1, when assigned to track 2 as hereinafter described, is supplied from output terminal *a* of unit AOU to input terminal *a* of unit TMU by first and second circuit paths, the first extending from said output terminal *a* over front contact *d* of relay F1T2SR, front contact *d* of relay 2TR, and over front contact *e* of relay HA2TSR to said input terminal *a*; and the second extending from said output terminal *a* over said front contact *d* of relay F1T2SR, front contact *b* of relay LT2SR, and over front contact *d* of relay HA1TSR to said input terminal *a*. Modulating frequency No. 2, when assigned to track 2 as hereinafter described, is supplied from output terminal *b* of unit AOU to input terminal *a* of unit TMU by the same first and second circuit paths just described except that front contact *d* of relay F2T2SR supplied modulating frequency No. 2 to said circuit paths in place of front contact *d* of relay F1T2SR supplying modulating frequency No. 1 to those paths.

Having thus described in general the control circuits for the apparatus of our invention, we will now describe the operation of the circuits and apparatus in several specific examples of controlling the movement of trains from the receiving yard to a location near the hump approach track preparatory to the movement of each train over the hump into the classification yard, and the operation of the circuits and apparatus in several specific examples of controlling the movement of each train, one at a time, from said location into the classification yard.

As previously set forth the receiving apparatus of the engine A equipment is assumed to be tuned to be responsive to audio modulating frequency No. 1 and the receiving apparatus of the engine B equipment is assumed to be tuned to be responsive to audio modulating frequency No. 2. It will be further assumed, for a specific example, that the employee operating the receiving yard control panel decides to route train A over track 1 and train B over track 2 to their positions preparatory to humping each train. (For purposes of simplicity in the remainder of this description the operator of the receiving yard control panel will hereinafter be referred to as the yardmaster and the operator of the hump control panel will herein-after be referred to as the hump conductor.) The yardmaster, therefore, depresses controller F1T1PB to assign audio modulating frequency No. 1 (shove-up engine A receiver being tuned to that frequency) to shove-up track 1, and also depresses controller F2T2PB to assign audio modulating frequency No. 2 (shove-up engine B receiver being tuned to that frequency) to shove-up track 2. The engineman of each of the shove-up engines is informed, prior to said manipulations, which of the shove-up tracks he is to travel.

The depressing of controllers F1T1PB and F2T2PB as described above closes the previously traced pickup circuits for relays F1T1SR and F2T2SR, respectively, and these relays pick up and will remain picked up so long as their respective controller remains depressed, the controllers being of the stick type as previously described. The pickup of relay F1T1SR closes front contact *d* of that relay in the control circuits for the transmitting apparatus (FIG. 2), and modulating frequency No. 1, to which engine A equipment is responsive, is supplied to transmitter TMU over the previously described circuit including front contacts *d* and *e* of relays 1TR and HA1TSR, respectively. Similarly, the pickup of relay F2T2SR closes front contact *d* of that relay in the control circuits for the transmitting apparatus, and modulating frequency No. 2, to which engine B equipment is responsive, is also supplied to transmitter TMU over the previously described circuit including front contacts *d* and *e* of relays 2TR and HA2TSR, respectively. The carrier frequency of transmitter TMU is thus modulated by both

audio frequencies, and transmitted in that modulated form from antenna TANT of unit TMU to antennas ARANT and BRANT of receiver units ARU and BRU, respectively.

The receipt of the carrier signal modulated by the audio frequency to which each of the receiver units is tuned causes pickup of demodulator relays ASCR and BSCR to change the indications of indicators ACS and BCS, respectively, from the stop indication to the proceed indication as previously described, and engines A and B can proceed, when ready to do so, over their assigned shove-up tracks in the direction of the crest of the classification yard hump.

It is desired to point out that the indications given by the aforesaid indicators remain under the control of the yardmaster until each shove-up engine traveling its assigned shove-up track occupies the track circuited track section in the respective track. (The operation of the apparatus when one of said track sections is so occupied will be described hereinafter.) Therefore, the yardmaster may, up to the time of such occupancy, change the indication of each indicator from proceed to stop by pulling the proper depressed controller to return it to its undepressed position and thereby open the pickup circuit for the respective control relay F1T1SR or F2T2SR. The yardmaster may also cancel a proceed indication by depressing a controller which is interlocked with the controller which established that indication; thereby causing the latter controller to return to its normal or undepressed position. However, this manipulation will result in the assignment of another audio frequency to the respective shove-up track if said other audio frequency is not already assigned to some other shove-up track.

The back contacts of the control relays F1T1SR, F2T1SR, F1T2SR, and F2T2SR in each other's pickup circuits prevent the assignment of one audio frequency to more than one shove-up track at a time. These contacts also serve to provide an additional means to prevent more than one audio frequency being assigned to any one track during the same period of time. It is believed that this will be readily apparent from a brief examination of the pickup circuits for said control relays.

We will now assume that the engineman of engine A, having received the afore-described proceed indication, proceeds over his assigned shove-up track 1 toward the hump and occupies track section 1T, thereby releasing track relay 1TR. The release of relay 1TR will open at front contact *d* of that relay the previously described circuit for supplying audio modulating frequency No. 1 to transmitter TMU (FIG. 2), and the indicator for shove-up engine A will therefore change its indication from proceed to stop to indicate to the engineman of engine A to take action to do so. The release of relay 1TR will also establish the previously described stick circuit for relay F1T1SR including back contact *c* of relay 1TR. Relay F1T1SR being maintained picked up by said stick circuit, the yardmaster no longer has control of the movements of engine A, the control of such movements now being in the hands of the hump conductor as described hereinafter. Maintaining relay F1T1SR in its picked-up position by said stick circuit prevents the yardmaster from pulling controller F1T1PB and thereby releasing relay F1T1SR. Back contact *b* of relay F1T1SR in the pickup circuit for relay F2T1SR prevents the assignment of modulating frequency No. 2 to track 1. Similarly, back contact *c* of relay F1T1SR in the pickup circuit for relay F1T2SR prevents the assignment of modulating frequency No. 1 to track 2. In this manner it is insured that modulating frequency No. 1 remains assigned to shove-up track 1, that is, under the control of track relay 1TR (or track relay HATR as hereinafter described).

We will now assume that the engineman of engine B, having received the afore-described proceed indication from engine B indicator, proceeds over his assigned shove-up track 2 toward the hump and occupies track section

2T, thereby releasing track relay 2TR. Similar circuit operation to that described for engine A now takes place. That is, audio modulating frequency No. 2 is no longer supplied to transmitter TMU, due to the opening of front contact *d* of relay 2TR. The engineman of engine B, therefore also receives a stop indication at this time. Back contact *c* of relay 2TR in the previously described stick circuit for relay F2T2SR closes to complete that stick circuit, thereby also removing control of relay F2T2SR from the receiving yard control machine and, therefore, from the yardmaster.

It will now be assumed, for purposes of this description, that the hump conductor decides to classify the cars of train B first rather than those of train A, although the manipulation is similar in either instance. The pump conductor, therefore, moves lever SCL on the hump control panel from its off position to position T2 to select track 2 and permit the engineman of engine B to begin car humping operations. As previously set forth, relay LOPR which repeats the off position of lever SCL is sufficiently slow to release that front contact *a* of that relay will remain closed for a sufficient period of time after lever SCL is moved from its off position to allow lever SCL to attain its T2 position, thereby closing the previously described pickup circuit for relay LT2SR, picking up that relay and closing its stick circuit including its own front contact *a*. The subsequent release of relay LOPR opens the pickup circuit for relay LT2SR, but the relay is maintained picked up over its said stick circuit. The pickup of relay LT2SR closes front contact *b* of that relay in the modulating frequency No. 2 supply control circuit to input terminal *a* of transmitter TMU, thereby again closing that circuit and again controlling indicator BCS for engine B from its stop to its proceed indication. It will be noted that the hump conductor, if he so desires, can at this time cancel the proceed indication for engine B by returning lever SCL to its off position and give a proceed indication for engine A by moving the lever to its T1 position. However, as pointed out hereinafter, such operation can only be performed up until the time engine B enters track section HAT.

The engineman of engine B having again received a proceed indication, as previously set forth, now moves his train into track section HAT, thereby releasing track relay HATR. The release of relay HATR opens at front contact *b* of that relay the pickup circuit for relay HA2TSR which also releases, its stick circuit over front contact *a* of relay 2TR having been previously opened. The opening of front contact *a* of relay 1TR in the stick circuit for relay HA1TSR when train A entered track section 1T, prepared the release of relay HA1TSR but said stick circuit was again closed when relay LT2SR picked up and closed its front contact *c*. Therefore, the opening of front contact *a* of relay HATR in the pickup circuit for relay HA1TSR, when engine B enters track section HAT, does not release relay HA1TSR. Furthermore, the release of relay HA2TSR, closes the second pickup circuit for relay HA1TSR over back contact *b* of relay HA2TSR. Relay HA2TSR having been released as described, its stick circuit is opened at its own front contact *a* and the relay cannot again be picked up so long as front contact *b* of relay HATR is maintained open by engine B occupying track section HAT. Therefore, relay HA1TSR cannot be released so long as engine B occupies track section HAT as the relay is maintained picked up over back contact *b* of relay HA2TSR. Although relay LT2SR can be released and relay LT1SR picked up by the hump conductor changing the position of lever SCL at this time, the modulating frequency supply control circuit for supplying modulating frequency No. 1 to transmitter TMU and including front contact *b* of relay LT1SR, cannot be closed as the circuit is open at front contact *d* of relay HA2TSR. Therefore, a proceed indication to permit engine A to enter track section HAT

cannot be given so long as train B occupies track section HAT.

The engineman of engine B may proceed with the car humping operations of his train so long as the hump conductor permits lever SCL to remain in position T2. The hump conductor can cancel the proceed indication for engine B at any time by moving lever SCL to the off position, thereby stopping train humping movements by engine B, and can permit such operations to be resumed by engine B by return of lever SCL to T2 position, and again giving the engineman of engine B a proceed indication.

When shove-up engine B has, by said car humping operations, reduced the size of its train sufficiently that track section 2T is vacated and only track section HAT is occupied, relay 2TR will again pick up. This will open back contacts *b* and *c* of relay 2TR in the pickup and stick circuits for relays LT2SR and F2T2SR, respectively; however, back contacts *d* of relay HATR and *c* or relay HA2TSR in said pickup and stick circuits, respectively, will remain closed thereby maintaining relays LT2SR and F2T2SR picked up at this time. Therefore, no change in the positions of these relays takes place at this time. The closing of front contact *d* of relay 2TR in the transmitter supply control circuits does not serve to close the alternate circuit for supplying audio frequency No. 2 to transmitter TMU because this circuit remains open at this time at front contact *e* of relay HA2TSR. The closing of front contact *a* of relay 2TR in the stick circuit for relay HA2TSR causes no change in the position of relay HA2TSR as its stick circuit is open at its own front contact *a*. Engine B may, therefore, continue its car humping movements, no change in the positions of any of the relays, except relay 2TR, taking place when track section 2T is vacated.

When engine B has completed its humping operations it may return to the receiving yard either by moving over the crest of the hump and returning by some return route not shown in the drawings, or by a back-up movement into track section 2T and thence to the receiving yard. If engine B returns by said back-up movement, a proceed indication for the engine to make such movements can be given to the engineman by the hump conductor until the engine vacates section 2T. At that time, back contacts *c* or relays 2TR and HA2TSR are both open and relay F2T2SR will release opening its front contact *d* in the audio frequency No. 2 supply circuit to transmitter TMU, unless the yardmaster previously failed to open the pickup circuit for relay F2T2SR by pulling the depressed controller F2T2PB. If the yardmaster did not so open said pickup circuit, the engineman of engine B will continue to receive a proceed indication. If the yardmaster did open said pickup circuit, he can give a proceed indication to engine B by again depressing controller F2T2PB. However, the route by which a shove-up engine returns to the receiving yard is immaterial to our invention and for the purposes of this description it will be assumed that engine B moves over the crest of the hump and returns to the receiving yard by said return route not shown.

When engine B moves over the crest of the hump and vacates track section HAT, relay HATR picks up and the following relay operation takes place. The closing of front contact *b* or relay HATR closes the pickup circuit to relay HA2TSR which also picks up. The picking up of relay HA2TSR completes, at back contact *c* of that relay, the opening of the stick circuit for relay F2T2SR which releases providing the yardmaster has previously pulled controlled F2T2PB and returned it to its undepressed position. The opening of back contact *d* of relay HATR completes the opening of the pickup circuits for relay LT2SR which releases providing this relay was not previously released by the hump conductor returning lever SCL to its off position when the car humping operations were completed. The apparatus

is now back in its normal condition and the indicator for engine B gives the engineman a stop indication. Engine B can now return to the receiving yard either running on said stop indication, or by the yardmaster again depressing controller F2T2PB to pickup relay F2T2SR in the manner previously described and thereby giving the engineman of engine B another proceed indication on which to return to the yard by said return route. The hump conductor can now move lever SCL to position T1 and permit the engineman of engine A to commence car humping movements. The operation of the apparatus of our invention in controlling the indications of indicator ACS for the car humping movements of engine A is believed readily understood from the previously described operations in controlling the movements of engine B and, therefore, it is not considered necessary to describe the operations of the apparatus for said movements of engine A. The similarity in operation is readily apparent.

In order to point out the purpose of relay LOPR in FIG. 1 it will now be assumed that engine A has completed its humping operations, and has returned to the receiving yard. It will be further assumed that engine B has another train of cars to be classified and has been assigned to track 1 for these operations. It will also be assumed that the hump conductor failed to return lever SCL to the off position following the car humping operations of engine A. The yardmaster depresses controller F2T1PB to assign frequency 2 (and engine B) to track 1 and relay F2T1SR picks up. The further operation of the circuits and apparatus, being similar to that described for the previous movements of engine B, this operation will not be described in detail but it will be assumed that the engineman of engine B receives a proceed indication and moves over track 1 and finally occupies track 1T, thereby releasing track relay 1TR. The release of relay 1TR opens at front contact *d* of that relay the circuit for supplying modulating frequency No. 2 to transmitter TMU and the indicator for engine B changes from proceed to stop. The release of relay 1TR also closes back contact *b* of that relay in the pickup circuit for relay LT1SR. Having assumed, as set forth previously, that the hump conductor failed to return lever SCL to its off position and left it in its T1 position following the car humping movements of train A, the pickup circuit for relay LT1SR would now be closed over back contact *b* of relay 1TR were it not for the open front contact *b* of relay LOPR in said pickup circuit, and relay LT1SR would pick up to continue to supply over its front contact *b* modulating frequency No. 2 to transmitter TMU. However, the open front contact *b* of relay LOPR in the pickup circuit for relay LT1SR requires that lever SCL be returned to its off position, thereby picking up relay LOPR, before relay LT1SR can pick up following its employment for previous car humping movements on track 1. Contact *a* of relay LOPR in the pickup circuit for relay LT2SR performs a similar function for relay LT2SR.

From this description it is apparent that with apparatus of our invention arranged as shown in the drawings, an economical train control system is provided for controlling the movements of trains from a receiving yard to a location preparatory to car humping operations in a hump or gravity type classification yard, and for control of the car humping movements themselves without the danger of a train performing such operations being "side-swiped" by another train where multiple tracks lead to the hump approach track. However, it is to be understood that our invention is not confined to receiving yard and gravity type classification yard installations, but may be employed in any installation where multiple tracks converge to form a single or main track.

Although we have herein shown and described only one form of apparatus embodying our invention, it is understood that various changes and modifications may be

made therein within the scope of the appended claims without departing from the spirit and scope of our invention.

Having thus described our invention, what we claim is:

1. In a train control system, in combination, a plurality of yard tracks converging to form a main track, a first track section in said tracks extending from a point just beyond the point at which said main track is formed to the clearance point in each said yard track, an additional track section in each said yard track extending from the clearance point for the respective track in a direction away from said main track to a predetermined point in the track, a track circuit for each said track section each including a track relay, a plurality of manually operable controllers, a transmitter for transmitting independent of the rails of said track sections a plurality of signals, means controlled by said controllers for selectively assigning a different one of said signals to a different one of said yard tracks; means controlled by the last mentioned means and by the track relay for the track section in each said yard track for activating said transmitter to transmit, when the respective track section is unoccupied, the signal assigned to that yard track; a plurality of receivers each tuned to a different one of said signals, a plurality of actuatable indicators one for each said receiver each indicator normally giving a stop indication and capable of giving a proceed indication when actuated, means controlled by each said receiver for actuating the associated indicator when that receiver is receiving the signal to which it is tuned, an additional manually operable controller having normal and multiple operated positions, and means controlled by said additional controller in one of its operated positions and the track relay for one of said yard track sections for reactivating transmission of the signal assigned to the respective yard track following an interruption of the transmission of that signal occasioned by the occupancy of that yard track section.

2. In a train control system, in combination, a plurality of yard tracks to be traveled by trains and converging to form a main track, a first insulated track section extending from a point just beyond the point at which said main track is formed to the clearance point in each of said yard tracks, an insulated track section in each said yard track each section extending from the clearance point for that track in a direction away from said main track to a predetermined point on the respective track, a track circuit for each said track section each including a track relay, a transmitter for transmitting signals independent of the rails of said tracks, a receiver on the engine of each said train, each receiver responsive to one of said signals different than that to which any other receiver is responsive, a plurality of manually operable controllers, means controlled by said controllers for selecting each said yard track and selectively assigning any unassigned one of said signals to the selected yard track; means controlled by the last mentioned means, the track relay for the track section in each selected yard track, and the track relay for said first track section for activating said transmitter to transmit the respective assigned signal when the first track section and the track section for the respective selected yard track are unoccupied; a cab indicator on each said engine each indicator normally giving a stop indication and capable of giving a proceed indication, means controlled by said receiver on each said engine for actuating said indicator on that engine to give a proceed indication when said transmitter is transmitting the signal to which that receiver is responsive, a manual control lever for selecting at different times each said yard track; and means controlled by said manual control lever, the track relay for said first track section and the track relay for the track section in the yard track then selected by the lever, for reactivating the transmission of the signal assigned to that selected yard track following an interruption of that signal occasioned by the occupancy of one of those track sections.

3. In a train control system, in combination, a stretch of track including a first and a second adjoining track section, a track occupancy detector for each said track section, a transmitter for transmitting a signal independent of the rails of said track sections, an engine to travel said track sections, a receiver on said engine responsive to said signal, an actuatable indicator on said engine normally giving a stop indication and capable of giving a proceed indication when actuated, means controlled by said receiver for actuating said indicator when said transmitter is transmitting said signal, a first manually operable controller having normal and actuated positions, means controlled by said controller in its actuated position and by said track occupancy detector for said first track section for actuating said transmitter to transmit said signal when the first track section is unoccupied, a second manually operable controller having normal and actuated positions; and means controlled by said second controller in its actuated position and said track occupancy detectors for reactivating, following an interruption of said signal occasioned by the occupancy of one of said track sections, said transmitter to transmit said signal so long as the second controller is in its actuated position.

4. In a train control system, in combination, a stretch of track including a track section, a track occupancy detector for said track section, a transmitter for transmitting a signal independent of the rails of said track section, an engine to travel said track section, a receiver on said engine responsive to said signal, an actuatable indicator on said engine normally indicating stop and capable of indicating proceed when actuated, means controlled by said receiver for actuating said indicator when said transmitter is transmitting said signal, a first manually operable controller having normal and actuated positions, means controlled by said controller in its actuated position and by said track occupancy detector for actuating said transmitter to transmit said signal when said track section is unoccupied, a second manually operable controller having normal and actuated positions, and means controlled by said second controller in its actuated position and by said track occupancy detector for actuating said transmitter to transmit said signal when said track section is occupied following a previous transmission of said signal.

5. In a train control system, in combination, a plurality of yard tracks to be traveled by trains and converging to form a main track, a first track section extending from a point just beyond the point at which said main track is formed to the clearance point in each of said yard tracks, a track section in each said yard track each extending from the clearance point for that track in a direction away from said main track to a predetermined point on the respective yard track, a track occupancy detector for each said track section, a transmitter for transmitting a plurality of signals independent of the rails of said tracks, a receiver on the engine of each said train each responsive to one of said signals different than that to which any other receiver is responsive, a plurality of manually operated circuit controllers, means controlled by said controllers and said track occupancy detectors for selectively assigning any unassigned one of said plurality of signals to any one of said yard tracks and activating said transmitter to transmit the assigned signal so long as said first track section and the track section for the respective yard track are unoccupied, an actuatable indicator on each said engine each indicator normally giving a stop indication and capable when actuated of giving a proceed indication, means controlled by the receiver on each said engine for actuating the indicator on that engine when said transmitter is transmitting the signal to which that receiver is responsive, another manually operated circuit controller for selecting each said yard track; and means controlled by said other circuit controller, the track occupancy detector for said first track section, and the track occupancy detector for

the track section in the yard track selected by said other circuit controller for reactivating said transmitter to transmit the signal assigned to that yard track following an interruption of the transmission of that signal occasioned by the occupancy of one of those track sections.

6. In a hump type railway car classification yard having multiple yard tracks leading to a single track in approach to the hump, in combination, a track occupancy detector for each said yard track, a transmitter for transmitting a plurality of signals independent of the rails of said tracks, a plurality of engines to travel said tracks, a receiver on each said engine each tuned to a different one of said signals, a plurality of manually operable controllers having normal and operated positions, means controlled by each controller in its operated position for assigning a different one of said signals to one of said yard tracks, means controlled by the last mentioned means and the track occupancy detector for said one of said yard tracks for activating said transmitter to transmit the assigned signal when that track is unoccupied to within a predetermined distance of said single track, an actuatable indicator on each said engine normally indicating stop and capable when actuated of indicating proceed, means controlled by the receiver on each said engine for actuating the indicator on that engine when said transmitter is transmitting the signal to which that receiver is tuned, an additional manually operable controller having a normal position and an operated position for each said yard track, and means controlled by said additional controller in each operated position and the track occupancy detector for the respective yard track for that position for reactivating transmission of the signal assigned to that track following an interruption of the transmission of that signal occasioned by occupancy of the track.

7. In a train control system, in combination, a plurality of yard tracks converging to form a main track, a track section in each said yard track each extending from the clearance point for that track in a direction away from said main track to a predetermined point on the yard track, a track circuit for each said track section each including a track relay, a plurality of manually operable controllers each having normal and operated positions, a transmitter for transmitting independent of the rails of said track sections a plurality of signals, means controlled by each said controller in its operated position for assigning one of said signals to one of said track sections; means controlled by said last mentioned means and the track relay for each track section for activating said transmitter to transmit, when that track section is unoccupied, the signal assigned to that track section; a plurality of engines to travel said tracks, a receiver on each said engine each tuned to a different one of said signals, an actuatable indicator on each said engine each normally indicating stop and capable when actuated of indicating proceed, means controlled by said receiver on each said engine for actuating said indicator on that engine when that receiver is receiving the signal to which it is tuned, an additional manually operable controller having normal and multiple operated positions, and means controlled by said additional controller in one of its operated positions and the track relay for one of said track sections for reactivating transmission of the signal assigned to the respective track section following an interruption of the transmission of that signal occasioned by the occupancy of that track section.

8. In a train control system, in combination, a plurality of yard tracks converging to form a main track, a first insulated track section extending from a point just beyond

the point at which said main track is formed to the clearance point in each of said plurality of yard tracks, an insulated track section in each of said plurality of yard tracks each section extending from the clearance point for that track in a direction away from said main track to a predetermined point on the respective track, a track circuit including a track relay for each said track section, a transmitter for transmitting a signal over a carrier channel independent of the rails of said tracks, a plurality of frequencies for modulating said signal, a receiver on the engine of each train to travel said yard tracks each receiver responsive to said signal and including a frequency selector responsive to one of said frequencies different than each of those to which the other frequency selectors are responsive, manually operable controllers for selectively assigning a different one of said frequencies to each of said yard tracks; means controlled by said manually operable controllers, by the track relay for said first track section, and by the track relay for the track section in each respective yard track for modulating said signal by each respective assigned frequency when said first track section and the track section in the respective yard track are unoccupied; and manually controlled means partially controlled by each said track relay for reactivating the modulation of said signal by the frequency assigned to each yard track following a previous modulation by the frequency assigned to that yard track and an interruption thereof by the occupancy of the track section in that yard track.

9. In a hump type railway car classification yard having a single track in approach to the hump and a plurality of tracks converging into said single track, in combination, means for transmitting independent of the rails of said tracks a different signal assigned to the engine of each train to travel said tracks, signal receiving means on each said engine responsive only to the signal assigned to that engine; an indicator on each said engine controlled by the signal receiving means, and normally giving a stop indication and operable to give a proceed indication when the signal assigned to that engine is received; a plurality of manually operable controllers, means controlled by said controllers for selectively assigning a different one of said signals to each of said plurality of tracks and actuating said transmitting means to transmit the assigned signals, a track occupancy detector for each of said plurality of tracks, means controlled by the track occupancy detector for each of said plurality of tracks for deactivating said transmitting means to interrupt the transmission of the signal assigned to that track when the track is occupied within a predetermined distance from the point of convergence with said single track, another manually operated controller, and means controlled by said other controller and each said track occupancy detector for selecting at different times each of said plurality of tracks and reactivating said transmitting means to transmit the signal assigned to that track when the track is occupied within said predetermined distance following a previous transmission of that signal.
